US00D962750S

(12) **United States Design Patent** (10) **Patent No.:** **US D962,750 S**
(45) **Date of Patent:** **** Sep. 6, 2022**

(54) **CABLE HANGER**

(71) Applicant: **Cambria County Association for the Blind & Handicapped**, Johnstown, PA (US)

(72) Inventors: **Timothy Joseph Wedding**, Johnstown, PA (US); **Paul Edward Martin**, Johnstown, PA (US)

(73) Assignee: **Cambria County Association for the Blind and Handicapped**, Johnstown, PA (US)

(**) Term: **15 Years**

(21) Appl. No.: **29/804,366**

(22) Filed: **Aug. 19, 2021**

Related U.S. Application Data

(63) Continuation of application No. 29/780,259, filed on Apr. 23, 2021, now Pat. No. Des. 930,461, which is a continuation of application No. 29/717,780, filed on Dec. 19, 2019, now Pat. No. Des. 919,418.

(57) **CLAIM**

The ornamental design for a cable hanger, as shown and described.

DESCRIPTION

FIG. 1 is a first isometric view of the cable hanger;

FIG. 2 is a second isometric view of the cable hanger;

FIG. 3 is a top view of the cable hanger;

FIG. 4 is a bottom view of the cable hanger;

FIG. 5 is a left view of the cable hanger;

FIG. 6 is a right view of the cable hanger;

FIG. 7 is a back view of the cable hanger; and,

FIG. 8 is a front view of the cable hanger.

The broken lines in the drawings depict environmental subject matter only and form no part of the claimed design.

1 Claim, 6 Drawing Sheets
